UNITED STATES PATENT OFFICE.

JOHN SKELTON, OF BARNUM, MINNESOTA.

STAKE-HOLDER RELEASE.

SPECIFICATION forming part of Letters Patent No. 727,009, dated May 5, 1903.

Application filed August 29, 1902. Serial No. 121,459. (No model.)

To all whom it may concern:

Be it known that I, JOHN SKELTON, a citizen of the United States, residing at Barnum, in the county of Carlton and State of Minnesota, have invented certain new and useful Improvements in Stake-Holder Releases, of which the following is a specification.

My invention relates to improvements in stake-holder-releasing means, its object being to provide means for so holding the retaining-stakes of flat-cars and logging-cars that the bottoms of all the stakes can be released when desired to allow logs to roll off the side of the car.

To this end my invention consists in the features of construction and combination hereinafter particularly described and claimed.

In the accompanying drawings, forming part of this specification, Figure 1 is a partial side elevation of part of a flat-car embodying my features of invention. Fig. 2 is a front elevation of the stake-holder and releasing means. Fig. 3 is a side elevation showing the side sill of the car in section. Fig. 4 is a plan view, and Fig. 5 is a section on line $x-x$ of Fig. 2 with the parts in unlocked position.

In the drawings, A represents the side sill of the car.

B represents the stake-holder, secured by bolts 2 to the side sill of the car and provided with an inwardly-projecting wing 3, secured by bolts 4 to the floor of the car. The stake-holder is formed with a central stake-opening 5, having its front side open. Supported upon the vertical pivot 6 in the holder at one side of the opening 5 is the latch 7. Having rotatable support in the holder at the opposite side of the opening is a vertical shaft 8, carrying at its upper end an eccentric cam 9. The free end of the latch 7 is formed with a curved groove 10 to receive the curved side of the cam 9, as shown in Fig. 4, to hold the latch in locked position. When the shaft 8 is

turned to bring the flat side of the cam toward the free end of the latch, the latch will be free to turn into open position, as illustrated in Fig. 5.

The lower end of the shaft 8 is connected by the lever-arm 11 and link 12 with a clamp 13, secured upon the rod 14. The rod 14 is slidably supported underneath the side of the car, as shown in Fig. 1.

15 represents an actuating-lever for the rod 14, having pivotal support 16 upon the side sill of the car and projecting downwardly between the pins 17, carried by the rod 14. A series of similar stake-holders are intended to be provided for the different stakes and to have their releasing means similarly connected with the rod 14.

In operation when it is desired to unload the car the handle 15 is actuated to release the latches 7 through the medium of the rod 14 and connected mechanism. The weight of the logs against the stakes will force their lower ends out of the stake-holders, allowing the logs to roll off the side of the car.

Having now described my invention, what I claim as new, and desire to secure by Letters Patent, is—

1. In combination, a stake-holder having one side open, a pivoted latch normally closing the open side of said holder, and a rotatable cam working in connection with the free end of said latch.

2. In combination, a stake-holder provided with an open side, a pivoted latch normally closing the open side of said holder, a locking-cam for said latch, an actuating-rod, and a connection between said cam and rod.

In testimony whereof I affix my signature in presence of two witnesses.

JOHN SKELTON.

Witnesses:

H. S. JOHNSON,
THERESA KANE.
